(57) **CLAIM**

The ornamental design for a pet harness, as shown and described.

DESCRIPTION

FIG. 1 is a left elevation view of a first embodiment of a pet harness, shown fastened in a first configuration, and in condition of use on a pet;

FIG. 2 is a bottom, front, left perspective view of the pet harness of FIG. 1, shown unfastened and flat in a second configuration;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a rear elevation view of the pet harness of FIG. 1, shown fastened in a first configuration;

FIG. 10 is a front elevation view of a second embodiment of a pet harness;

FIG. 11 is a top, rear, left perspective view thereof;

FIG. 12 is a rear elevation view thereof;

FIG. 13 is a top plan view thereof;

FIG. 14 is a bottom plan view thereof;

FIG. 15 is a left side elevation view thereof; and,

FIG. 16 is a right side elevation view thereof.

In the drawings, the broken lines depict environmental subject matter only and form no part of the claimed design.

1 Claim, 10 Drawing Sheets
